(57) **CLAIM**

The ornamental design for a digital audio disc player for automobile, as shown and described.

DESCRIPTION

FIG. 1 is a front, top and right side perspective view of a digital audio disc player for automobile showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken lines depict portions of the digital audio disc player for automobile in which the design is embodied that form no part of the claimed design. The oblique shade lines in FIG. 1 and FIG. 2 show translucency.
